(57) **CLAIM**

The ornamental design for a massage roller, as shown and described.

DESCRIPTION

FIG. 1 is a top perspective view of a massage roller having sinusoidal ridges for massaging a person's muscle with an end shown in broken lines;

FIG. 2 is a bottom perspective view the massage roller shown in FIG. 1;

FIG. 3 is a front view of the massage roller shown in FIG. 1;

FIG. 4 is a rear view of the massage roller shown in FIG. 1; FIG. 5 is a left view of the massage roller shown in FIG. 1; FIG. 6 is a right view of the massage roller shown in FIG. 1;

FIG. 7 is a top view of the massage roller shown in FIG. 1;

FIG. 8 is bottom view of the massage roller shown in FIG. 1; and,

FIG. 9 is a cross sectional view of the massage roller shown in FIG. 1.

The broken lines shown on the top and bottom ends are for the purpose of illustrating portions of the massager roller, which form no part of the claimed design.

1 Claim, 5 Drawing Sheets
